UNITED STATES PATENT OFFICE.

HARRY O. SEBRING, OF SEBRING, OHIO.

HEADLIGHT.

1,131,797.

Specification of Letters Patent. Patented Mar. 16, 1915.

Application filed July 29, 1914. Serial No. 853,869.

To all whom it may concern:

Be it known that I, HARRY O. SEBRING, a citizen of the United States, residing at Sebring, in the county of Mahoning and State of Ohio, have invented a new and useful Headlight, of which the following is a specification.

This invention relates to headlights for use upon vehicles and is more particularly 10 adapted to be used upon automobiles.

The object of this invention is to provide a headlight which will not only illuminate the road directly in front of the vehicle when traveling in a direct course, but which 15 will also illuminate the path in which a vehicle is traveling when turning a corner or traveling around a curve or bend in the road.

Another object is to provide a headlight 20 in which a central lamp and side lamps are contained within a casing whereby the light from the lamps may be thrown forwardly and angularly to opposite sides.

A further object is to provide a headlight 25 which is simple in construction, efficient, and inexpensive.

With these objects in view the invention consists in the novel construction and arrangement of parts, hereinafter described, 30 illustrated in the accompanying drawings, and particularly pointed out in the appended claim, it being understood that various changes in the form, proportions, size and minor details of construction may be 35 made without departing from the spirit or sacrificing any of the advantages of the invention.

In the drawings: figure 1 is a front elevation of my improved headlight. Fig. 2 40 is a vertical section on the line 2-2 of Fig. 1, other parts being broken away for the purpose of illustration. Fig. 3 is a diagrammatic view of the lights for illuminating the path of the vehicle at either side thereof, 45 showing a system of wiring for said lights.

Similar numerals of reference indicate corresponding parts throughout the several figures of the drawings.

The numeral 1 indicates the usual casing 50 of a headlight provided with a door 2 having a plain glass panel 3 therein, said door being hinged at 4 in the usual manner and provided with any suitable form of latch 5. Located within the casing is the usual lamp 55 6 provided with a suitable reflector 7 throwing the rays of light from the lamp, straight

ahead through the lens 8. The lamps 9 and 10 which are adapted to throw beams of light to the right and left of the road are provided with reflectors 11 and 12 and lenses 13 and 14, respectively.

Any suitable system of wiring such as that shown in Fig. 3 may be used, whereby both of the lamps 9 and both lamps 10 are connected to a common source of electrical 65 current 15. A switch 16, which may be made in the form of a push button if desired, is adapted to close the circuit through the lamps 9 and a similar switch 17 controls the circuit through the lamps 10. By this 70 construction either the two lamps 9, or the two lamps 10, may be lighted whenever desired by operating the proper switch. The central lamp 6, in each casing will of course remain lighted as it will preferably be located in a different circuit from the side 75 lights 9 and 10. When a bend or turn in the road is approached by the vehicle the driver will close the switch which controls the lamps upon the side of the vehicle toward the turn in the road and as his central lamps will continue to burn he will have a clear view of the road directly in front of the vehicle and also a clear view around the bend in the road so that he will be able to 80 observe obstructions which may be in the road beyond the bend, thus reducing the possibility of accidents and collisions.

If desired, both of the side lamps 9 and 10 may remain lighted as well as the forward lamps 6, thus enabling any obstructions to be visible at either side of the road and also enabling the driver to observe any turns or bends, in the course of the road, with which he may be unfamiliar. 95

Although this headlight has been described as provided with electric lamps, it will of course be understood that any suitable form of light may be used, such as oil, gas or acetylene burners. 100

It will of course, be understood that the lamps 9 and 10 may be combined in a single casing, if desirable, separate from the central lamp 6, although the form shown is a more convenient and preferable form. 105

Although the drawings and above specification disclose the best mode in which I have contemplated embodying my invention I desire to be not limited to the details of such disclosure, for, in the further practical application of my invention, many changes in form and construction may 110

be made, as circumstances require or experience suggests, without departing from the spirit of the invention, within the scope of the appended claim.

I claim:

In a headlight, the combination of a casing, a door hingedly connected to said casing, a transparent panel provided upon said door, a central lamp located within said 10 casing, a conical reflector located around said central lamp, side lamps contained within said casing, each of said side lamps provided with an individual conical reflector, the reflector for the central lamp direct- 15 ing the rays of light straight ahead and the reflectors for the side lamps directing the

rays of light at an angle to the light from the central lamp, said central lamp adapted to remain continuously lighted, independent circuits for each of said lights and selective 20 means for closing or breaking either or both of said circuits, said selective means being independent of the movement of the machine.

In testimony that I claim the above, I 25 have hereunto subscribed my name in the presence of two witnesses.

HARRY O. SEBRING.
